T. LUMSDEN.
TOOL AND LIKE GRINDING MACHINE,
APPLICATION FILED FEB. 8, 1911.
1,032,758.

Patented July 16, 1912.

FIG. 1.

UNITED STATES PATENT OFFICE.

THOMAS LUMSDEN, OF GATESHEAD, ENGLAND.

TOOL AND LIKE GRINDING MACHINE.

1,032,758.

Specification of Letters Patent. Patented July 16, 1912.

Application filed February 8, 1911. Serial No. 607,363.

To all whom it may concern:

Be it known that I, THOMAS LUMSDEN, a subject of the King of Great Britain and Ireland, and a resident of Gateshead, in the county of Durham, England, have invented certain new and useful Improvements in or Relating to Tool and Like Grinding Machines, of which the following is a specification.

10 This invention relates to grinding machines of the type in which the grinding wheel or disk is moved relatively to the tool or cutter to be sharpened, and the invention has for its object to provide a machine for 15 grinding or sharpening the tools or cutters of large machine tools such as lathes and slotting, shaping, planing and like machines.

I will fully describe my invention with reference to the accompanying drawings 20 wherein—

Figure 1 is a side elevation, partly in section, of a grinding machine embodying my improvements, and Fig. 2 is a section on the line X—Y therein.

25 Referring to the drawings *a* is a driving shaft mounted in a bed-plate *b* and having a driving pulley *c* and a loose pulley *d*. On the driving shaft *a* is mounted an oscillating frame or column *e*, and in bearings at the 30 upper end of the frame or column *e* is mounted a shaft *f* carrying an annular or cup-shaped grinding wheel or disk *g*. The frame or column *e* is oscillated by a connecting rod *h* pivoted to the frame or column *e* at *j* and a crank pin *k* on a disk *m* which is 35 driven by and from the driving shaft *a*. The disk *m* is driven from the driving shaft *a* by a pulley *n* thereon, a belt *o*, a pulley *p*, variable speed mechanism contained in a 40 gear box or casing *q*, and a pinion *r* gearing with the toothed periphery of the crank disk *m*. The variable speed mechanism comprises toothed wheels *s*, *s*¹ and *s*² rotating with and free to slide on the shaft *t* of the 45 pulley *p* and corresponding toothed wheels *u*, *u*¹ and *u*² on the shaft *v* of the pinion *r*. By meshing the wheels *s*, *s*¹ and *s*² in the known manner with the wheels *u*, *u*¹ and *u*² respectively the speed of the shaft *v* and hence the speed of the oscillations of the 50 frame or column *e* can be varied without variation of the speed of the driving shaft *a*. The crank pin *k* is adjustable as to throw or eccentricity in any suitable manner for the 55 purpose of varying the angle through which the frame or column *e* oscillates. Conven-

iently the crank pin *k* projects through a slot *w* and is mounted on a screwed spindle *x* which is mounted within the crank disk *m* and provided with a bevel wheel *y* gearing with a complementary wheel *z* on a spindle *2* disposed within the hollow shaft of the disk *m* and furnished with a handwheel *3* so that by operating said handwheel the screwed spindle *x* can be rotated to adjust the crank pin *k* toward or away from the center of the disk *m*. The crank pin *k* can be adjusted by operating the handwheel *3* while the frame or column *e* is being oscillated. The grinding wheel or disk *g* is 70 driven direct from the driving shaft *a* by a pulley *4* thereon, a belt *5* and a pulley *6* on the grinding wheel shaft *f*.

The tool or cutter to be ground is fixed in a holder *7* angularly adjustable in a carrier *8* which is angularly adjustable by a pivot *9* on a turntable carriage *10* mounted on a compound slide *11* carried by a turret *12* mounted on the bed-plate *b* whereby the tool or cutter can be adjusted as required to position against the annular face or rim *13* of the grinding wheel or disk.

On the rotation of the driving shaft *a* the grinding wheel or disk *g* is driven thereby and the disk *m* is simultaneously driven by the shaft *a*, and by means of the crank pin *k* and connecting rod *h* the frame or column *e* is oscillated on the driving shaft *a* and carries the annular face or rim *13* of the grinding wheel or disk *g* across the tool or cutter fixed in the holder *7*, and a true face or surface is ground on the tool or cutter. As both the grinding wheel shaft *f* and the disk *m* are driven from the center of oscillation of the frame or column *e*—i. e. 90 the driving shaft *a*—the oscillations of the frame or column *e* do not affect the driving of the grinding wheel *g* or the disk *m*.

What I claim and desire to secure by Letters Patent is:—

1. In a tool grinding or sharpening machine the combination with a driving shaft mounted in bearings in a bed-plate, of a frame or column trunnioned at its lower end on said driving shaft, a grinding wheel or disk mounted at the upper or free end of said frame or column, an adjustable holder for holding the tool to be ground, means for rotating said grinding wheel or disk direct from said driving shaft, means for oscillating said frame or column during the grinding operation, and means for varying the 105 110 115

angular length or stroke of the oscillations of said frame or column, said means being capable of adjustment while said frame or column is being oscillated.

- 5 2. In a tool grinding or sharpening machine the combination with a driving shaft mounted in bearings in a bed-plate, of a frame or column trunnioned at its lower end on said driving shaft, a grinding wheel or disk 10 mounted at the upper or free end of said frame or column, an adjustable holder for holding the tool to be ground, means for rotating said grinding wheel or disk direct from said driving shaft, means for oscillating said frame or column during the grinding 15 operation, and means for varying the speed of the oscillations of said frame or column with respect to the speed of said driving shaft.
- 20 3. In grinding machines, the combination of a frame or column mounted on a trunnion, means for oscillating said frame or column on said trunnion, means for varying the speed of the oscillations of said frame 25 or column, means for varying the angular length or stroke of the oscillations of said frame or column, a shaft mounted on said frame or column, an annular or cup-shaped

grinding wheel or disk carried by said shaft, means for rotating said shaft and grinding 30 wheel or disk, and a tool holder mounted on an adjustable carriage.

4. In grinding machines, the combination of a driving shaft, a frame or column mounted on said driving shaft, means for 35 oscillating said frame or column on said driving shaft said oscillating means being driven by and from said driving shaft, variable speed mechanism for varying the speed of the oscillations of said frame or 40 column, an adjustable crank pin for varying the angular length or stroke of the oscillations of said frame or column, a shaft mounted on said frame or column, an annular or cup-shaped grinding wheel or disk 45 carried by said shaft, means for rotating said shaft said rotating means being driven by and from said driving shaft, and a tool holder mounted on an adjustable carriage.

In witness whereof I have hereunto signed 50 my name in the presence of two subscribing witnesses.

THOMAS LUMSDEN.
